UNITED STATES PATENT OFFICE.

AUGUSTINE J. POCOCK, OF DAYTON, OHIO.

OIL-DISPENSING PUMP.

1,262,697.

Specification of Letters Patent. Patented Apr. 16, 1918.

Original application filed June 26, 1915, Serial No. 36,443. Divided and this application filed August 7, 1916. Serial No. 113,493.

To all whom it may concern:

Be it known that I, AUGUSTINE J. POCK, a citizen of the United States, residing at Dayton, in the county of Montgomery and State of Ohio, have invented certain new and useful Improvements in Oil-Dispensing Pumps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in pumps of a type which is designed for discharging liquids in measured quantities and is of the single-acting single cylinder type. The objects of the invention are several, principally among which is to provide a generally improved form of construction in which the body of the pump may be cast in one piece thus facilitating the manufacture as well as economizing in the cost of manufacture. The present application is divided from my pending application, Serial No. 36,443, filed June 26, 1915. With reference to the general design or construction of the pump, the improved characteristics thereof relate to means for fastening in the cylinder and for forming the body of the pump for the application of insulation. The body of the pump is cast in one piece in such form as to enable it to be bored so that the tube may be tight and the recess for the insulating material provided.

Preceding a more detail description of my invention, reference is made to the accompanying drawings of which Figures 1 and 2 are vertical front and side elevations, respectively, showing the pump intact; Fig. 3 is a vertical sectional elevation of the lower portion of the pump broken at the middle to facilitate the illustration; Fig. 4 is an enlarged illustration of the driving gear box and reversing gears on the line 4—4 of Fig. 1; Fig. 5 is a side elevation of the driving gears and adjunctive parts; Fig. 6 is a sectional view of the head and adjacent parts of the discharge pipes showing a form of vacuum breaker on the interior of said head; Fig. 7 is a cross-sectional view of the cylinder on the line 7—7 of Fig. 3. Fig. 8 is a sectional view of the sealing device for the stop, the same being on the line 8—8 of Fig. 1.

In a detail description of the invention, similar reference characters indicate corresponding parts in both the description to follow and the accompanying drawings.

Referring more specifically to these drawings, 1 designates the casting forming the main portion or body of the pump and terminating in a lower base portion 1' constructed for a rigid attachment to a suitable support, and an upper head 28. This body or casting is especially constructed for the attachment of oppositely disposed inclosing plates 2—2, and an inner cylinder 3. The making of the body or casting 1 in one piece, as described, enables it to be bored with much facility so that the cylinder 3 may be driven tightly into its position, the upper portion of said cylinder being flared outwardly against a corresponding flaring portion 45" of the casting, and forced into an annular groove 45^a, as plainly shown in Fig. 3. The lower end of the cylinder 3 is driven tightly against flanges 45 and 45' of said casting which provide an effective seat for that end of said cylinder. This construction very conveniently provides for the application of a jacket of insulating material 4 to be placed around the cylinder 3 within the surrounding space. The insulating material 4 may be such as cork or any other material having the proper efficiency for maintaining the cylinder at a desirable temperature. This insulating jacket 4 may be conveniently placed in position after the cylinder 3 and casting 1 are assembled, the detachable plates 2—2 enabling access to be had for this purpose and for the purpose of assembling the insulation and replacing it whenever such becomes necessary. The top or head 28 provides a chamber 28' which is closed by a cap 46 and into which is discharged the liquid upon each upstroke of the piston, to be presently described. The lower portion of the pump is provided with an initial inlet chamber 24 which is fed through an inlet 43 and above said chamber 24 the pump is provided with a hand opening which is closed by a screw-cap 44 and through which access may be had to the suction valve, presently described. The suction valve 25 seats in a suitable opening above the chamber 24 and controls the admission therefrom.

When not affected by the discharge stroke of the piston 21, the said valve 25 is maintained upon its seat. In order to apply a suitable additional pressure on said valve 5 when so seated and to maintain an effective seating, a spring 26 is provided thereon. This spring is affected by a stirrup or frame 23 which is secured to the bottom of the piston 21 in a position to engage said spring 10 just as the said piston approaches its seat. The weight thereof of the piston and the parts moving therewith is instrumental in insuring such proper seating of the suction valve 25. The spring 26 affords a suitable elastic intervening part for effectively maintaining a proper seating of the valve 25. The valve 25 opens into an upper chamber 25' from which the oil is drawn through the inlet or discharge valve 27. This valve 15 20 25 is carried by the piston 21 and opens upon each descent of said piston and closes upon the return upstroke thereof. A yoke 21' provides a suitable means for connecting the piston rod 22 which passes through a suitable packed opening in the cap 46. A driving rack 8 is connected to the piston rod 22 and is held in mesh with the gear 9 by a roller 40. The said rack 8 extends into a gear box 5 mounted upon an air pipe 30 30 and discharge pipe 29 which extend from the pump head 28. The rack 8 is driven from a system of reversing gears which forms the subject matter of my co-pending application. This system of gearing is, 35 however, illustrated in Figs. 4 and 5 of the drawings where it will be seen that the rack 8 is in constant mesh with a driving gear 9 pinned to a shaft 6 journaled in the upper part of the gear casing or box 5. The driving gear 9 is adapted to be driven in opposite directions by gears 10 and 12, the former of which is mounted on a shaft 7 journaled in the lower part of the gear box 5 and operated from a crank handle 35. 40 45 The gear 12 is fixed to the driving gear 9 both of which move with the shaft 6. A pinion 11 also runs on the shaft 7 and meshes with the gear 12. Reverse movements are imparted to the driving gear 9 and to the rack and piston by the gears 10 and 11 and these gears are controlled by clutch members 15 and 16 which are fixed, respectively, to said gears. Coöperating with said clutch members 15 and 16 are 50 55 clutch members 14 and 17, respectively, which are slidably mounted on the shaft 7. The outer ends of these clutch members 14 and 17 have each a spiral cam slot which provides inner and outer cam surfaces 19 and 19' and end abutments 18 and 18'. The clutch members 14 and 17, as before stated, slide upon the shaft 7, and are rotated by double-acting cams 20 and 20' and the tapered surfaces 19 and 19' of the clutch 60 65 members, and the rotary movement takes

place when said cams engage the abutments 18 and 18'. Means are provided for preventing the clutch members 14 and 17 rotating while the cams 20 and 20' are moving against the incline surfaces 19 and 19' and 70 until the abutments 18 and 18' are engaged to rotate said clutch members. This means consists of brakes or shoes 31 suitably arranged to engage the periphery 31' of said clutch members. These friction devices 75 may be suitably mounted on arms 32 conveniently mounted on the pump frame, as shown in Fig. 5, wherein one of said arms 32 is shown to be connected to a cross bar 32'. Suitable pressure is applied to said 80 shoe by springs 33 conveniently attached at one end to the arms 32 and the other ends of which are provided with adjusting connections in the form of hook-bolts 34'. From the foregoing description, it will be 85 seen that the rack 8 and therewith the pump piston are given reciprocatory movement from the gear 9, one direction of such movement being imparted from the crank handle 35 to the shaft 7, clutch members 4 and 90 5, and gear 10, and the other direction of movement being imparted through the clutch members 16 and 17, and gears 11 and 12. Owing to the differential of the gears, the idle stroke of the piston is obtained in 95 a much shorter space of time which is an advantage due to the system of gears described.

The discharge pipe 29 leading from the chamber 28' communicates with a chambered head 34 from which a discharge spout 36 extends. A suitable length of hose (not shown) may be attached to the discharge pipe 36. The discharge of oil through said spout and hose has a tendency to siphon and to thereby interfere with correct discharges or measurements of oil. Inasmuch, however, as siphoning cannot occur without what is commonly termed a vacuum at the head of the discharge pipe, I have provided what 100 may be termed a vacuum breaker as a preventative consisting of a diaphragm 37 mounted in the top of the head 34 and having an orifice 38 and a button 39 of suitable material such as leather secured to the cap 105 of said head. By the said diaphragm closing against said button, the exclusion of air from the chamber below takes place, thereby constituting what may be termed an automatic vacuum breaker. The discharge 110 115 stroke of the piston is regulated through stops 41 arranged at suitable points along a rod 42 mounted between the head 28 and gear box 5. These stops may limit the piston to a one-half gallon, gallon, two gallon, 120 and two and a half gallon stroke, and the rod 42 is turned to bring said stops in or out of alignment with a shoulder 47 on the lower end of the rack 8. Such operation is given 125 said rod 42 by means of a hand rod or bar 130

48 suitably mounted. When a particular stop 41 is placed in position, it may be locked and sealed in such position. This is accomplished by means of a series of members 49, 5 one connected to each stop 41. The said members 49 have a screw-threaded connection with a rod 50 mounted adjacent to and parallel with the stop rod 42. The said members 49 have each a series of recesses 51 10 in which a sealing rod 52 lies. This rod may be sealed in any suitable manner. In the drawings I have shown the end thereof projected through an opening in a lug 53 on a side of the screening or filtering case 54.

15 Having described my invention, I claim,

20 1. In a pump structure, a cylinder comprising a casting providing an inlet chamber at one end and an outlet chamber at the other end, the portion of said casting above the inlet chamber having a seat and the portion below the outlet chamber having an inwardly lying flange in alinement with said seat and the inner surface of which is substantially of a flaring form, a cylinder the 25 lower end of which firmly engages said seat and the upper end of which firmly engages said flaring surface.

30 2. In a pump structure, a cylinder comprising a casting providing an inlet chamber at one end and an outlet chamber at the other end, the portion of said casting above the inlet chamber having a seat and the portion below the outlet chamber having an inwardly lying flange the inner surface of 35 which is of substantially a flaring form, a cylinder the lower end of which firmly engages said seat and the upper end of which firmly engages said flaring surface, an insulating jacket inclosing said cylinder between its attached ends, and covered openings in the side of said casting communicating with the space surrounding said insulating jacket and enabling access thereto.

40 3. In a pump, a cylinder comprising a casting providing an inlet chamber at one end and an outlet chamber at the other end, the portion of said casting above the inlet chamber having a seat and the portion below the outlet chamber having an inwardly lying 45 flange with a tapered surface in alinement with said seat, a cylinder the lower end of

which firmly engages said seat, and the upper end of which firmly engages said flaring surface, a piston movable in said cylinder, and an inlet valve carried by said piston. 55

4. In a pump, a cylinder comprising a casting providing an inlet chamber at one end and an outlet chamber at the other end, the portion of said casting above the inlet 60 chamber having an annular seat and the portion below the outlet chamber having an inwardly lying annular flange with a tapered surface in alinement with said seat, a cylinder the lower end of which firmly engages 65 said seat and the upper end of which firmly engages said tapered surface, and a piston within said cylinder and adapted to engage said seat when at the lowermost limit of its stroke. 70

5. In a pump, the combination with a pump body providing a lower inlet chamber, a piston cylinder rigidly engaging inwardly lying portions of said pump body, a suction valve controlling said inlet chamber, 75 a spring carried by said suction valve, a piston movable in said cylinder, and a frame member extending from said piston in a position to engage said spring when the piston is in the lowermost position of its travel and 80 whereby said suction valve is maintained upon its seat by elastic pressure.

6. In a pump of the character specified, the combination of a pump body having openings in the sides thereof closed by detachable plates, a cylinder lying inwardly from said openings, an insulating jacket surrounding said cylinder, a piston within said cylinder, an inlet valve carried by said piston, a suction valve below said inlet valve, 90 and elastic means interposed between the piston and said suction valve and whereby the suction valve is maintained upon its seat by elastic force when the piston has reached the lowermost position of its travel. 95

In testimony whereof I affix my signature in presence of two witnesses.

AUGUSTINE J. POCOCK.
